Primary Examiner — Brett Miller*Assistant Examiner* — Nader Abadir(74) *Attorney, Agent, or Firm* — Harpman & Harpman(57) **CLAIM**

The ornamental design for a food board, as shown and described.

DESCRIPTION

FIG. 1 is a top, front perspective view of my food board design.

FIG. 2 is a front elevational view thereof.

FIG. 3 is a rear elevational view thereof.

FIG. 4 is a left side elevational view thereof, the right side being a mirror image thereof.

FIG. 5 is a top plan view of the food board of my design; and,

FIG. 6 is a bottom plan view thereof.

1 Claim, 6 Drawing Sheets
